UNITED STATES PATENT OFFICE.

NATHAN E. HANSON, OF NEW YORK, N. Y., ASSIGNOR TO UNION SPECIAL MACHINE COMPANY, OF CHICAGO, ILLINOIS, A CORPORATION OF ILLINOIS.

RUFFLING AND SEWING MACHINE.

1,143,903.

Specification of Letters Patent. Patented June 22, 1915.

Application filed July 8, 1908. Serial No. 442,529.

To all whom it may concern:

Be it known that I, NATHAN E. HANSON, a citizen of the United States, residing at New York, in the county of New York, 5 State of New York, have invented certain new and useful Improvements in Ruffling and Sewing Machines, of which the following is a description, reference being had to the accompanying drawing and to the letters and figures of reference marked thereon.

This invention relates to new and useful improvements in sewing machines, and more especially to machines for ruffling and sewing, the object of the invention being to provide a machine wherein ruffles of all sizes from the largest to the "shadow" ruffling may be made, or the ruffling action may be stopped entirely, without stopping the action of the stitch-forming mechanism.

20 A further object of the invention is to provide a machine of the above character with guides for guiding various pieces of material, so that they may be secured to the strip being ruffled.

25 Further objects of the invention will in part be obvious, and will in part be herein-after more fully described.

The invention consists in the parts, improvements and arrangements hereinafter 30 shown and described.

In the drawings which show by way of illustration only one embodiment of the invention, Figure 1 is a front view of a sewing machine embodying my invention; the knee 35 shift being omitted from this view; Fig. 2 is a detail view of the mechanism for operating the ruffler shaft from the main shaft of the machine; Fig. 3 is a similar view from the opposite side, showing also the mechanism 40 for adjusting the throw of the ruffling mechanism; Fig. 4 is a detail view, showing the knee shift and its connection with the adjusting device for the ruffling mechanism; Fig. 5 is a detail view from the end of the 45 machine, showing the needles, the presser foot, the guides for the fabric and the ruffler; Fig. 6 is a detail view showing the operation of the ruffler in connection with the presser foot; and Fig. 7 is a cross section of 50 a seam made on one form of my invention. Fig. 8 is a sectional view through the segment plate showing the stop nut and the adjustable bolt.

The machine herein shown by way of 55 illustration, is similar in many respects to

that shown and described in the patent to Russel G. Woodward, No. 706,484, granted August 5th, 1902. It will be obvious, however, that from certain aspects the invention is not limited to this particular type of machine, but may be embodied in various types of ruffling and sewing machines.

The bed plate 1 has rising therefrom an overhanging arm 2, carrying a needle head 3 at its forward end, in which reciprocates a 60 needle bar 4, carrying needles 5, 5, at its lower end. Said needle bar is reciprocated by the needle lever 6, through the link 7, from the main shaft 8 in the well known manner.

The ruffling blade 9 is secured to a head 10, by suitable screws. Said ruffling head 10 is pivoted at 11 to the supporting arm 12, which is carried by the rock shaft 13 mounted in suitable bearings carried by the bed 70 plate 1. The shaft 13 at its rear end is provided with an arm 13', which is connected to the auxiliary shaft 13'', carrying an arm 14, to which is pivoted a link 15 in a manner shown in Patent 706,484, above referred to. 75 The forward end of the link 15 is provided with a bolt 16, carrying a pivot block, running in a curved slot 17, in the segment plate 18, pivoted at 18' to a lug carried by the frame of the machine. The segment 80 plate 18 is vibrated by means of an eccentric 19 carried by the main shaft 8, through an eccentric strap 20, which is pivoted at 21 to the said segment plate.

The mechanism above described is substantially the same as that shown in the patent to Woodward above referred to.

By adjusting the bolt 16 in the slot 17, toward and from the pivot point 18', the throw of the ruffler blade may be increased 95 or decreased, and if the pivot bolt 16 is brought so as to coincide with the axis of the pivotal connection 18', then no vibration whatever will be imparted through the link 15, and the ruffler will be thrown out of 100 action. The slot 17 is preferably curved concentrically about the pivotal connection between the link 15 and the arm 14 when the ruffling blade is at its extreme forward position. This construction will afford means 105 for holding the ruffling member the same distance from the needle at the forward end of its stroke during all its adjustments.

As a means for adjusting the throw of the ruffling blade, I have provided a rock shaft 110

22 which carries an arm 23, to which is pivoted a link 24. The opposite end of the link 24 is pivoted to the connecting bolt 16. The shaft 22 also is carried by suitable bearings formed in the bed plate 1 of the machine, and at its rear end is provided with an arm 25. A spring 26 is connected at one end to an eye 27, carried by the arm 25, and at its other end to a stud 28, carried by the head of the machine. Said spring 26 normally tends to hold the arm 25 raised, and the arm 23 lowered, which will hold the pivot bolt 16 at the lower end of the slot 17 in the segment plate 18. An adjustable screw 29 is carried by a lug 30, supported by the bed plate of the machine, and extends into the path of the arm 25, so as to limit its upward movement. A stop nut 31 serves to lock the adjustable screw 29 in various positions. A stop bolt 32 is mounted in the slot 17, and may be readily adjusted up and down in the slot to any position desired by loosening the nut carried thereby. This stop bolt serves to limit the upward movement of the pivot bolt 16. As a means for shifting the arm 25, I have shown herein a knee shift 33, which is pivoted at 34 to a suitable bracket 35 carried by the machine stand. A rod 36 is connected at 37 to the lever 25, and 30 at 38 to the knee shift 33.

In the operation of my device, the stop bolt 32 is so positioned in the slot 17, that when the bolt 16 is thrown against said stop bolt the largest size ruffle desired will be made. The stop screw 29 is properly set so as to determine the smallest size ruffle desired. The operator then by manipulating the knee shift 33 may, without stopping the machine, readily throw the link 15 so as to 40 make the largest size ruffle or the smallest size ruffle, or any intermediate size ruffle desired. When it is desired to stitch a certain distance without any ruffling whatever, the screw 29 is then so positioned that the 45 bolt 16 may be thrown down over the axis of the pivot 18'. The presser foot 39 has a stripper blade 40, secured thereto by suitable screws, and said stripper blade is located so as to extend down under the front portion 50 of the presser foot. The ruffling blade 9, as above noted, is pivotally connected with the arm 12, and a spring 41 engaging the under side of the ruffling blade see Figs. 1 and 6, normally tends to hold the ruffling blade 55 thrown up against the stripper blade 40. The strip of fabric A to be ruffled, is led through the guide 42 carried by an arm 43, rigidly secured to a block 44, attached to the bed plate of the machine. Said guide 42 is 60 so disposed that the strip of fabric A passes between the stripper blade 40 and the ruffling blade 9. The vibrations of the ruffling blade carry the fabric forward, forming the ruffles against the under side of the 65 stripper blade, which are held thereby in the

usual manner. I have also shown a fabric guide 46, for guiding a piece of fabric B. Said guide 46 is so located as to carry the fabric B underneath the ruffled strip, and is so constructed as to fold over the edge of the 70 fabric B on to the upper face of said fabric. I have also shown a tape guide 47, which is formed integral with the presser foot, and leads a strip of tape C down through a slot in the presser foot in front of the stitching 75 point. Said tape guide 47 is provided with means for folding the edges of the tape underneath, and is located so that said tape is led to the stitching mechanism, and a line of stitching passed therethrough adjacent each 80 edge of the tape. This tape is secured to the fabrics A and B so as to cover the raw edges of said fabrics.

It will be obvious from certain aspects of my invention, that various forms of fabric 85 guides may be used in connection with the ruffling mechanism herein shown and described, and that, therefore, the present disclosure is only one illustration of the capabilities of operation of my device.

The sewing machine is, of course, provided with the usual feeding mechanism and the mechanism for operating the ruffler is so timed when forming ruffles as to give to the ruffling blade a differential movement relative to the movement of the main feed. It will be obvious that instead of a ruffling blade technically known as such, other ruffling members may be substituted therefor. If the ruffling mechanism herein shown, operate upon elastic fabric such as knit goods, it is obvious that the ruffling action may be adjusted so that the elastic material will gather only sufficient to overcome the tendency to stretch, thus stitching said elastic 100 fabric evenly and smoothly to another material.

Having thus particularly described my invention, what I claim as new and desire to secure by Letters Patent is:

1. A sewing machine including in combination, a work support, a main shaft beneath the work support, stitch-forming mechanism and a ruffling member located above the work support and adapted to engage the underface of the fabric to be ruffled, an arm supporting said ruffling member, a rock shaft beneath the work support by which said arm is carried, means beneath the work support for vibrating said rock shaft from said main shaft, and means operable without stopping the stitch-forming mechanism for varying the throw of the ruffling member.

2. A sewing machine including in combination, a work support, a main shaft beneath the work support, stitch-forming mechanism and a ruffling member adapted to engage the underface of the fabric to be ruffled, an arm supporting said ruffling mem-

ber, a rock shaft beneath the work support by which said arm is carried, means beneath the work support for vibrating said rock shaft from said main shaft, including a 5 shiftable member for varying the throw of the ruffling member, and means for shifting said member without stopping the stitch-forming mechanism.

3. A sewing machine including in combination, a work support, stitch forming mechanism, a ruffling member, a rock shaft carrying said ruffling member, means for oscillating said rock shaft including a vibrating member, a link connected to said vibrating 15 member and to said rock shaft, and means for shifting the connection between said link and vibrating member without stopping the stitching mechanism, and a plurality of adjustable stops for limiting the movement of 20 said shifting means.

4. A sewing machine including in combination, a work support, stitch forming mechanism, a ruffling member, a rock shaft located beneath the work support and carrying 25 said ruffling member, means for vibrating said rock shaft including a slotted plate, a link connected to said slotted plate, and a stop nut located in said slot for limiting the movement of said link, and means for shifting 30 said link without stopping the stitching mechanism.

5. A sewing machine including in combination, a work support, stitch forming mechanism, a ruffling member, a rock shaft located beneath the work support and carrying 35 said ruffling member, means for vibrating said rock shaft including a slotted plate, a link, a bolt to which said link is pivoted, slidingly secured in said slot, a knee shift, 40 and means operated by said knee shift, for adjusting said bolt in said slot.

6. A sewing machine including in combination, a work support, stitch forming mechanism, a ruffling member, a rock shaft located 45 beneath the work support and carrying said ruffling member, means for vibrating said rock shaft including a slotted plate, a link, a bolt to which said link is pivoted, 50 slidingly secured in said slot, a knee shift, and means operated by said knee shift for adjusting said bolt in said slot, and adjustable stops for limiting the movement of said bolt.

7. A sewing machine including in combination, a work support, stitch forming mechanism, a ruffling member, a rock shaft located beneath the work support and carrying 55 said ruffling member, means for vibrating said rock shaft including a slotted plate, a link, a bolt to which said link is pivoted, 60 slidingly secured in said slot, a knee shift, means between said knee shift and said bolt, whereby said bolt may be adjusted in one direction in said slot, and a spring for moving 65 said bolt in the opposite direction.

8. A sewing machine including in combination, a work support, stitch forming mechanism, a ruffling member, a rock shaft located beneath the work support and carrying 70 said ruffling member, means for vibrating said rock shaft including a slotted plate, a link, a bolt to which said link is pivoted, slidingly secured in said slot, a knee shift, means between said knee shift and said bolt, whereby 75 said bolt may be adjusted in one direction in said slot and a spring for moving said bolt in the opposite direction, and adjustable stops for limiting the movement of said bolt.

9. A sewing machine including in combination, a work support, stitch forming mechanism, a ruffling member, a rock shaft, located beneath said work support, and having 80 an upwardly extending arm carrying said ruffling member, means for vibrating said rock shaft, including a pivoted segment plate, a link connecting said segment plate to said rock shaft, and means for shifting the connection between said segment plate and said link, including a rock shaft, a link 85 connecting said rock shaft to said first named link, and means for oscillating said last named rock shaft.

10. A sewing machine including in combination a work support, stitch forming mechanism, a ruffling member, a rock shaft located beneath said work support and having 90 an upwardly extending arm carrying said ruffling member, means for vibrating said rock shaft including a pivoted segment plate, a link connecting said segment plate to said rock shaft, and means for shifting the connection between said segment plate and said link, including a rock shaft, a link 95 connecting said rock shaft to said first named link, and means for oscillating said last named rock shaft, and adjustable stops for limiting the movement of said last named rock shaft.

11. A sewing machine including in combination, a work support, stitch forming mechanism, a ruffling member, a rock shaft located beneath said work support, and having 100 an upwardly extending arm carrying said ruffling member, means for vibrating said rock shaft, including a pivoted segment plate, a link connecting said segment plate to said rock shaft, and means for shifting the connection between said segment plate and said link, including a rock shaft, a link 105 connecting said rock shaft to said first named link, and means for oscillating said last named rock shaft, and adjustable stops for limiting the movement of said last named rock shaft.

110

12. A sewing machine including in combination, a work support, stitch forming mechanism, a ruffling member, a rock shaft located beneath said work support, and having 115 an upwardly extending arm carrying said ruffling member, means for vibrating said rock shaft, including a pivoted segment plate, a link connecting said segment plate to said rock shaft, and means for shifting the connection between said segment plate and said link, including a rock shaft, a link 120 connecting said rock shaft to said first named link, said last named rock shaft having an arm connected thereto and a knee shift connected to said last named arm, for oscillating said last named rock shaft.

125

130

said ruffling member, means for vibrating said rock shaft including a pivoted segment plate, a link connecting said segment plate to said rock shaft, and means for shifting the connection between said segment plate and said link including a rock shaft, a link connecting said last named rock shaft to said first named link, an arm connected to said last named rock shaft, a spring connected to said arm for moving said last named rock shaft in one direction, and a knee shift connected to said last named arm for moving the last named rock shaft in the opposite direction.

13. A sewing machine including in combination, a work support, stitch forming mechanism, a ruffling member, a rock shaft located beneath said work support, and having an upwardly extending arm carrying said ruffling member, means for vibrating said rock shaft including a pivoted segment plate, a link connecting said segment plate to said rock shaft, and means for shifting the connection between said segment plate and said link including a rock shaft, a link connecting said last named rock shaft to said first named link, an arm connected to said last named rock shaft, a spring connected to said arm, for moving said last named rock shaft in one direction, and a knee shift connected to said last named arm for moving the last named rock shaft in the opposite direction, an adjustable bolt located in the path of said arm, for limiting the movement thereof by said spring.

14. A sewing machine including in combination, a work support, stitch forming mechanism, a ruffling member, a rock shaft located beneath said work support, and having an upwardly extending arm carrying said ruffling member, means for vibrating said rock shaft, including a pivoted segment plate, a link connecting said segment plate to said rock shaft, and means for shifting the connection between said segment plate and said link, including a rock shaft, a link connecting said last named rock shaft to said first named link, an arm connected to said shaft, a spring connected to said last named arm for moving said last named rock shaft in one direction, and a knee shift connected to said last named arm for moving the last named rock shaft in the opposite direction, an adjustable bolt located in the

path of said last named arm for limiting the movement thereof by said spring, and an adjustable stop carried by said segment plate for limiting the movement of said last named arm by said knee shift.

15. A sewing machine including in combination a work support, a needle bar, a plurality of needles carried thereby, a tape guide for guiding a tape to said needles, a folding guide for guiding and folding the edge of the material, a guide for guiding a second piece of material between said tape and said first named material, a ruffling blade and means coöperating therewith, whereby said second material may be ruffled, a rock shaft pivoted beneath the work support and supporting said ruffling blade, means for operating said rock shaft, and means for varying the stroke of said rock shaft without stopping the movement of said needles.

16. A sewing machine including in combination a work support, a presser foot, a stripper blade carried by said presser foot and extending underneath the same, a ruffling member, a spring for yieldingly holding the free end of said ruffling member against the stripper blade, means for vibrating said ruffling member, including a rock shaft pivoted beneath the work support and supporting the ruffling member, means for operating the rock shaft and means for guiding a strip of material between the stripper blade and the ruffling member.

17. A sewing machine including in combination, a work support, a presser foot, a stripper blade carried by said presser foot, a ruffling member, means for supporting said ruffling member, a spring for yieldingly holding the free end of said ruffling member against the stripper blade, means for vibrating said ruffling member, and means for guiding a strip of material between the stripper blade and the ruffling member, means for guiding a strip of material underneath the ruffling member, and means for guiding a tape over said stripper blade.

In testimony whereof I affix my signature, in presence of two witnesses.

NATHAN E. HANSON.
